CROSS-FEED FOR CIGAR BUNCH
MACHINES

Herbert A. Burns, Forest Hills, N. Y., assignor to
International Cigar Machinery Company, a
corporation of New Jersey

Application May 31, 1940, Serial No. 338,056

1 Claim. (Cl. 131—81)

This invention relates to an improved cigar filler tobacco feed, and more particularly to the construction of the filler feeding channel thereof.

Hitherto, cigar filler feed channels have been equipped with parallel opposed walls. With parallel walls in a cigar filler feed channel, particularly when employed to form a wide shallow stream of cigar filler, the lengths delivered from the cross feed would be of non-uniform thickness across their width, thus causing soft or low spots in the filler column which impair the uniformity of the bunch charge subsequently separated from the filler column. These soft spots are one of the causes for the uneven burning of cigars. Another disadvantage exists in the making of small diameter cigars with the standard wide parallel cross feed, where too thin a charge is required to handle well.

A further disadvantage of the parallel walled cigar filler feeding channel was that where the operator of the machine did not fill out the sides of the channel near the vertical belts with cigar filler, no means existed to correct this uneven filling, and bunch charges of unequal thickness would subsequently be separated from the filler as a result.

One of the objectives of the present invention is to provide a means for eliminating the thinness of the cigar filler near the side walls of the feed channel, due in part to the tendency of an operator to distribute more filler in the center of the channel feed than near the side walls of the channel. This object is particularly important when considered in connection with the application of Henry H. Wheeler, Ser. No. 304,299, filed November 14, 1939, on which Patent No. 2,311,011 was issued February 16, 1943, where the accumulations of the cut cigar filler are made one above the other. There the error of uneven thickness rapidly increases in constantly having the thin sided and thick centered filler lengths accumulate one above the other, resulting in a recurring lack of uniformity, particularly soft or low spots in the bunch charges eventually separated from the assembled filler lengths.

Another object of the invention is to provide an improved manner for making cigar filler lengths of uniform density and the elimination of soft or low spots in bunch charges eventually separated from the filler.

A further object of the invention is to provide an improved means for the uniform densifying of the thin filler charge required in making small diameter cigars and for feeding a low column of filler which will be formed into higher columns of cut filler lengths.

With these and other objects not specifically mentioned in view, the invention consists in certain constructions and combinations hereinafter

fully described and then specifically set forth in the claim hereunto appended.

In the accompanying drawings which form a part of this specification and in which like characters of reference indicate the same or like parts:

Fig. 1 is a plan view of the improved cigar filler feeding channel;

Fig. 2 is a side elevation of the same;

Fig. 3 is a diagrammatic cross sectional view, on the line 3—3 of Fig. 1, of the broader part of the improved channel showing the usual shape of the cigar filler at this part when inserted by the operator;

Fig. 4 is a diagrammatic cross sectional view, on the line 4—4 of Fig. 1, of the narrower part of the improved channel showing the even distribution of the cigar filler when it arrives at the cutters, with certain parts omitted;

Fig. 5 is a plan view of the filler feed belts associated with mechanism for accumulating cut filler lengths in a vertical column, showing the charge separating knife and supporting fingers in an inoperative position;

Fig. 6 is a side elevation of the same showing the charge separating knife and supporting fingers in an operative position prior to cutting the filler length; and

Fig. 7 is a side elevation of the same subsequent to cutting the filler length and the raising of the cut length vertically in the column.

In carrying the invention into effect there is provided a plurality of feed belts arranged to form a cigar filler feeding channel, the vertical side walls of said channel being spaced, opposed, and converging toward one another in the direction of the cutters. The said converging side wall belts are supported by means preventing them from bending outward because of pressure by the filler within the channel. There is provided mechanism for driving said belts and vertical means for guiding and compacting the filler in the channel.

In the best forms of construction contemplated, said side wall belts begin converging at a certain constant rate toward the cutters from the broadest end of the channel. The said side walls may also be arranged to converge from any point between the end opposite to the cutters and the point where the cigar filler is cut in desired lengths. The said side walls may also be arranged to converge from any point between the end opposite to the cutters and some point short of where the cigar filler is cut in desired lengths.

Referring to Figs. 1 and 2 of the drawings, the frame 10 supports cross bars 11 which carry a feed table 12, the frame 10 also carrying a feed belt 13, and one end of the converging feed belts 14 and 15. A bracket 16 integral with the frame 10 supports the other ends of the converging

belts 14 and 15, and the pedestal 17 mounted on the frame 10 supports the cam shaft 18 and the fulcrum stud 19.

The filler tobacco is placed in the tapered filler feeding channel formed by the horizontal feed belt 13 and the two converging vertical feed belts 14 and 15. The horizontal belt 13 is supported by pulleys 20, 21 and 22, and adjustable pulley 23, mounted on the frame 10. The converging vertical side wall belts 14 and 15 are supported by pulleys 24 and 25 mounted on the frame 10, and by flanged pulleys 26 and 27 carried on the adjustable slide 28 on the end of bracket 16. The horizontal belt is driven through a sprocket 29 on a shaft 30, and the converging vertical belts 14 and 15 are driven by bevel gears 31 which mesh with bevel gears 32 on shaft 30a, the bevel gears 31 being fixed on the shaft of the pulleys 24 and 25. The sprocket 29 on shaft 30 is driven by a chain 33, the other end of which runs over a sprocket on shaft 30a which is intermittently driven by suitable means such as shown in the patent to Bronander, No. 1,740,571, granted December 24, 1929.

The filler tobacco L progressively placed in the tapered feed channel formed by the horizontal feed belt 13 and the converging side wall belts 14 and 15 is intermittently advanced and passes between a set of stationary guides 34 and under a leaf guide plate 35 and compacter plate 36 on which the leaf guide is hinged and under means 37 for compacting the filler vertically.

Figs. 3 and 4, which are diagrammatic cross section views of Fig. 1 on the lines 3-3 and 4-4 respectively, show the cigar filler before it has been subjected to the action of the converging belts 14 and 15 and after the cigar filler has been subjected to the converging action of belts 14 and 15 respectively. In passing from the outer part of the channel towards the cutters, the width of the cigar filler is gradually narrowed by converging belts 14 and 15 forming a filler delivered to the cutters of uniform thickness and the elimination of soft or low spots in bunch charges eventually separated from the filler.

Figs. 5, 6 and 7 show the manner in which the cut filler lengths are accumulated vertically. With the cutting platform 38, as shown in Fig. 6, in its lowermost position, the tobacco layer L is advanced onto the same by the feed belts 13, 14 and 15. The movable upper corrugated knife 39 is then lowered to firmly hold the filler tobacco, whereupon the cutting platform 38 with an attached lower corrugated knife 40 is raised into an intermediate position, thereby cutting off the advanced tobacco layer L thereon. Then the fingers 41 are withdrawn from the position in which they supported the surplus tobacco from the preceding cycle to their outermost position, as shown in Fig. 5, thereby dropping this surplus tobacco on top of the cut layer on the cutting platform thus forming a tobacco column F on the same. Cutting platform 38 then completes its up stroke lifting column F up against insert plate 42 which is part of a transfer pocket, as disclosed in the above mentioned Wheeler application Ser. No. 304,299, thereby raising said insert plate 42 into top position, as shown in Fig. 7 which limits the thickness of charge F to be cut.

The oscillating knife blade 44 moves forward to sever charge F in the transfer pocket. The supporting fingers 41 then move into their in posi-

tion so as to register with the slot ways 43 in the now raised cutting platform 38, as shown in Fig. 7. Cutting platform 38 then returns to its down position leaving the cut filler lengths F on the interposed fingers 41, as shown in Fig. 6, and the upper corrugated knife 39 returns to its up position preparatory to the repetition of the cycle set forth above.

The feed control mechanism controlling the operation of the above members is the same as that mentioned in the Wheeler application referred to above. When the accumulated tobacco column F is of sufficient magnitude, this mechanism provides for temporarily stopping the feeding of additional filler onto the cutting platform, until such time as additional filler is required in column F.

The present construction, while it has other uses, in its preferred embodiment described is employed in a cross feed for feeding a tobacco stream crosswise of the main feed of a cigar machine, as shown in the above mentioned application of Wheeler, and operates to correct the tendency of the operator to put more filler in the center of the channel than near the side by means of converging side walls whereby the thin edge of the filler is telescoped sidewise making the filler of uniform thickness and density thereby eliminating soft or low spots from the bunch charges subsequently separated from the filler.

The present invention enables cigar filler to be fed into a broad channel in thin layers and by gradual compacting forms this thin broad layer into a thicker filler layer of uniform density particularly desirable in making small size cigars.

It should be noted that while it is ordinarily easier for the operator to feed the filler tobacco in a thin broad layer, this has the disadvantage that any variation from normal in the thickness of the layer fed by the operator tends to bear a rather high ratio to normal thickness. When this broad layer is compacted sidewise into a narrower layer, these variations are decreased and moreover any remaining form a smaller percentage of the total thickness.

It is to be understood that the form of the invention, herewith shown and described, is to be taken as a preferred example of the same, and that various changes in the shape, size and arrangement of parts may be resorted to, without departing from the spirit of the invention, or the scope of the subjoined claim.

53 What is claimed is:

In a cigar machine, the combination with a plurality of feed belts arranged to form a filler feeding channel, mechanism for driving said belts, a transverse cutter adjacent one end of said belts, said belts being arranged to gradually converge toward said cutter to compress said filler laterally to make the lateral sides of the filler of the same density as the center of the filler, means constructed and arranged to assemble lengths of filler cut by said cutter vertically with the upper surface of one length in contact with the bottom surface of another length and compact the assembled lengths, and a device for separating a bunch charge from the assembled and compacted lengths.

HERBERT A. BURNS.
